DRILL GRINDING MACHINE

Edward Bausch, Rochester, and William L. Flad,
Irondequoit, N. Y., assignors to Bausch & Lomb
Optical Company, Rochester, N. Y., a corpora-
tion of New York

Application June 2, 1932, Serial No. 614,952

3 Claims. (Cl. 51—219)

This invention relates to devices for grinding the points of twist drills and the like and more particularly it has reference to means for properly locating and holding the drill in contact with the grinding element.

One of the objects of our invention is to provide a drill grinding machine which will be convenient and simple in structure yet efficient in operation. Another object is to provide a drill grinding machine having optical means for locating and positioning the drill. A further object is to provide an improved chucking device for holding twist drills in position to be ground. These and other objects and advantages reside in certain novel features of construction, arrangement and combination of parts as will hereinafter be more fully described and pointed out in the appended claims.

Referring to the drawings:

Fig. 1 is a side elevation of a drill grinding machine embodying our invention, with parts broken away.

Fig. 2 is an enlarged top plan view of same.

Fig. 3 is an enlarged sectional view through the drill holding means and support.

Fig. 4 is an enlarged view of a detail of the drill holding means.

Fig. 5 is a fragmentary view showing the angularly adjustable support for the drill holding means.

Fig. 6 is a sectional view on line 6—6 of Fig. 5.

Fig. 7 is a view showing the bushing on a drill in separated relation to the collet.

Fig. 8 is a side view of the bushing.

A preferred embodiment of our invention is shown on the drawings wherein 10 indicates a base which carries the vertical column 11 having a threaded portion 12. Slidably and swingably mounted on column 11 is the arm 13 having a clamping member 14 for holding it in adjusted position. A nut 155 cooperating with the threaded portion 12 serves as an adjustable limiting stop for the arm 13. Mounted on arm 13 is a motor M which is supplied with electric current by means of connecting cord 16. The motor M has a vertically positioned shaft 17 on which is mounted the disk-shaped grinding element 18 having a flat, annular grinding surface 19 on its upper surface. A suitable guard member 20, attached to the frame of motor M serves to enclose the grinding element 18 except on the top side.

Fixedly mounted on column 11 is a bracket member 21 having an integral boss 22 provided with a curved slide portion 23. An arm 24, provided with an arcuate slot 25, is adapted to be

adjusted along the slide portion 23 and held in adjusted position by means of screw 26 which passes through the slot. Threadedly mounted on the end of arm 24 is a screw 27 having oppositely disposed bearing recesses 28 and 28' in which are mounted the pivot members 29 and 30 for supporting the tubular bearing member 31. Slidably and rotatably mounted within bearing member 31 is the sleeve 32 having an enlarged end portion 33 provided with a tapered inner wall 34. Rotatably mounted within the sleeve 32 is the tube 35 having an integral head portion 36 and a threaded portion 37 which cooperates with the threaded portion on collet chuck 38. A bushing 39, which is split as at 40, is slipped over the end 10 of the drill D to be ground, as shown in Fig. 7. The bushing fits snugly over the end of the drill and a separate, individual bushing is preferably supplied for each drill size. The bushing and drill are positioned within the collet chuck 38 and 20 the threaded tube 35 is turned so as to draw the tapered wall of the collet into engagement with the tapered wall 34 of the sleeve 32 thereby 25 clamping the bushing and drill firmly in position, as shown in Fig. 3.

Secured to sleeve 32, adjacent its top, is a collar 41 having a clamping screw 42 for releasably clamping the collar so as to engage sleeve 32. The collar 41 has two projecting lugs 43 which are 180 degrees apart and adapted to enter two correspondingly spaced notches 44 formed on bearing member 31. The sleeve 32 and its associated parts may thus be slid axially in bearing member 31 against the action of coil spring 45 and rotated 180 degrees for a purpose to be herein- 30 after described. A rod 46 is slidably mounted within tube 35 and is used for ejecting and positioning the drill.

Pivotedly mounted on bracket 21 is a rod 47 adapted to swing upward about a horizontal axis, 40 the downward movement of said rod 47 being limited by the adjustable stop screw 48 carried by bracket 21. Adjustably mounted on the free end of rod 47 is the tube 49 within which the microscope 50 is slidably mounted to provide for 45 focusing adjustments. The microscope 50 is provided with a suitable cross hair or fiducial line, not shown, to enable the operator to properly position a twist drill in the chuck.

In grinding a twist drill properly it is necessary to have the sharp edge or dead center in the axial plane of the drill. The web of the drill should be symmetrically positioned with respect to the axial plane and the two cutting lips should make equal angles with the drill axis. 55

Corresponding points on the two cutting edges are therefore 180 degrees apart.

In operation of our device, the drill D is clamped in the chuck and positioned in alignment with the microscope 50 as shown in Fig. 2. The operator then loosens clamping screw 42 on collar 41 thereby permitting the sleeve and drill D to be rotated with respect to member 31 until one of the cutting lips is aligned with a cross hair when viewed through the microscope 50. The sleeve and drill are then moved up against the action of spring 45 and rotated until the lug 44 cooperates with the notch 44 on the opposite side member 31. The other cutting lip is then viewed through the microscope and if it coincides with the cross hair, the drill is properly located in the chuck. If not, the screw 42 is again loosened and the sleeve turned with respect to the collar 41 and adjustments made so that upon rotating the drill and sleeve 180 degrees corresponding points on the two cutting lips will coincide with the cross hair. When this condition is reached the drill is properly located in the chuck.

The arm 47 carrying the microscope 50 is then swung upwardly out of the way and the chuck and drill are rotated, to the right as seen in Fig. 2, about the pivots 29 and 30 thereby bringing the point of the drill into contact with the grinding surface 19 of the rotating grinding wheel 18. The chuck is held in the hand and rocked back and forth to the right of the vertical plane passing through the pivots 29 and 30 as the drill contacts with the grinding surface. This provides for a suitable clearance for the cutting lips. For most purposes an angle of 59 degrees between the cutting lip and the axis provides an efficiently operating drill. For certain purposes, however, it is desirable to utilize a different angle and so means is provided for adjusting this angle by loosening screw 26 and angularly adjusting the bracket arm 24, the angle being indicated on a scale 51 carried by boss 22. After one lip has been ground, the sleeve is pulled out to disengage lug 43 and turned 180 degrees to permit the lug 45 to engage the notch 44 on the opposite side. This action turns the drill 180 degrees and so locates the drill in proper position to grind the other lip. If the drill has been broken off so there is considerable grinding to be done, the drill may be raised up from the wheel 18 by means of screw 27 so that small increments can be fed gradually down toward the stone. In the finishing position, however, the screw 27 must be positioned with its head engaging the top of bracket 24 as shown in Fig. 3.

To prevent undue wearing in one path on the wheel, the motor and wheel may be laterally adjusted by loosening screw 14 and swinging the arm 13 together with the motor and grinding wheel. A bracket 52, projecting outwardly from member 21, carries a rotatably mounted block 53 in which a diamond 54 is eccentrically mounted so that the diamond can be moved over the grinding surface 19 for the purpose of truing it.

From the foregoing it will be apparent that we have provided an improved means for accurately and conveniently grinding twist drills. Our device is especially adapted for sharpening twist drills of relatively small sizes. The drills can be inspected and sharpened without removing them from the chuck. The indexing lugs on collar 42 provide an accurate and convenient means for locating the drill in the chuck so that both cutting lips can be ground quickly. The optical device provides an especially accurate means for locating the drills in the chuck and its advantage in connection with the smaller drills is readily apparent. The use of the bushing 39 at the end of the drill affords a firm holding device which keeps the drill from being bent or forced out of axial alignment. Our device enables an operator to quickly sharpen small twist drills with great accuracy and precision. The microscope further permits the operator to inspect and check the drill after it has been ground. Various modifications can obviously be made without departing from the spirit of our invention.

We claim:

1. A drill grinding machine having in combination drill holding means comprising a bearing member mounted to turn about an inclined axis, a sleeve slidably and rotatably mounted within said member, a collet and cooperating threaded tube for holding a drill within said sleeve, a collar adjustably mounted on said sleeve, means for clamping said collar in adjusted position, and cooperating indexing means on said collar and member for locating the drill with respect to said member.

2. A drill grinding machine comprising a vertical support, an arm mounted to turn about said support in a horizontal plane, a grinding element mounted on said arm to rotate about a vertical axis, a bracket carried by said support, an arm pivotally carried by said bracket, drill holding means for holding a drill in contact with said element, said holding means being longitudinally movable and pivotally mounted on said arm to turn about an inclined axis, a rod movably mounted on said bracket and a microscope mounted on said rod, said microscope having fiducial means for locating the drill relative to said element.

3. A drill grinding machine having in combination drill holding means comprising a bearing member adjustably mounted to turn about an inclined axis, means for adjusting said bearing member along said axis, a sleeve slidably and rotatably mounted within said member, a collet and cooperating threaded tube for holding a drill within said sleeve, a collar adjustably mounted on said sleeve, means for clamping said collar in adjusted position, and cooperating index means on said collar and member for locating the drill with respect to said member.

EDWARD BAUSCH.
